PACKAGING CONTAINER

William L. Miller, Skokie, Ill., assignor to Continental Can Company, Inc., New York, N.Y., a corporation of New York

Filed Mar. 13, 1962, Ser. No. 69,241

Term of patent 14 years

(Cl. D58—17)

Fig. 1.

Fig. 2.

The dominant features of my design reside in the packaging container of the configuration shown having a double row of substantially triangular protrusions arranged alternately around the bottom thereof, all as shown.

I claim:

The ornamental design for a packaging container, as shown and described.
